UNITED STATES PATENT OFFICE.

DE WITT CLINTON PRESCOTT, OF DULUTH, MINNESOTA, ASSIGNOR TO THE YORK STRUCTURAL STEEL COMPANY, OF NEW YORK, N. Y.

ROLLING APPARATUS.

SPECIFICATION forming part of Letters Patent No. 603,474, dated June 28, 1898.

Application filed March 22, 1895. Serial No. 542,757. (No model.)

To all whom it may concern:

Be it known that I, DE WITT CLINTON PRESCOTT, of Duluth, in the county of St. Louis and State of Minnesota, have invented certain new and useful Improvements in Rolling Apparatus, of which the following is a specification.

The present invention relates to rolling-mills which embody in their construction a plurality of sets of opposed rolls which act upon and reduce a slab of iron or steel to a finished product—as, for instance, that form known as an “I-beam.”

The object of the invention is to provide for and in a mill of this class a construction which will permit each set of rolls to be adjusted independently of the other set, as well as permitting the several sets to be adjusted collectively.

I will describe a rolling apparatus or mill embodying my invention and then point out the novel features in the claims.

In the accompanying drawings, Figure 1 is a side elevation of a rolling apparatus embodying my improvement. Fig. 2 is a plan view thereof. Fig. 3 is a transverse section on line $\alpha\alpha$, Fig. 1.

Similar letters of reference designate corresponding parts in the figures.

I have shown my invention as being embodied, for the sake of illustration, in a rolling apparatus of the form and construction pointed out in Patent No. 410,724, granted September 10, 1889, to L. D. York, and to which I refer for a more detailed description of the parts common to the two inventions. I do not, however, in so illustrating and describing it limit myself to the particular apparatus disclosed in that patent, but wish to cover the improvement as applied to any apparatus, of which the one shown in the patent is a type as regards the presence of a plurality of sets of forming-rolls.

Referring to the drawings, A A' are the upper and lower rolls, and B B' are the side rolls, deriving motion from any suitable source. The rolls A A' are, as usual, supported in housings C C to have an adjustment toward and away from each other, while the rolls B B' may be carried in side blocks D D', the latter being movable in side frames E E'.

In the process of rolling structural shapes—

e. g., the so-called “I-beam”—it is necessary to adjust the upper and lower rolls A A' toward and away from each other, as well as to impart to the side rolls B B a corresponding movement, in order that the slab may be formed upon all sides and reduced to the desired dimensions of the structural shape. Occasion may also arise during the rolling of structural shapes when it is desirable that, instead of adjusting the rolls A A' B B all together, the rolls A A' should be adjusted while the rolls B B remain stationary, or, conversely, the rolls B B should be adjusted while the rolls A A' remain stationary. I will now describe the means whereby these several adjustments may be effected—namely, a collective adjustment of all the rolls or an independent adjustment of the rolls A A' or an independent adjustment of the rolls B B.

F F are screws entering nuts secured to the upper portion of the housings C C and by means of which the upper roll A may be moved toward or away from the lower roll A', as pointed out in the before-mentioned patent.

To each screw F F, secured to its upper extremity and projecting vertically upward therefrom, is a short shaft G, having a bearing in a bushing g, which is carried by a standard g', surmounting the housing C. The shaft G is provided with a spline g², engaging in a longitudinal recess in the bearing-surface of the bushing g. Consequently as the screw F is rotated the shaft G will be carried lengthwise of the bushing g, rotating with the latter, while to prevent a lengthwise movement of the bushing itself I may form the bushing with a circumferential groove g³, in which projects a circular tongue g⁴ from each member of the separable standard g'. A worm-wheel G' is secured to each bushing g, by means of which the same may be rotated.

It is essential that the power for effecting the adjustment of the rolls A A' B B should be in a measure independent of the power for rotating those rolls, since the two movements are not dependent one on the other.

I have shown as a source of power for the adjustment mechanisms a pair of vertical engines H, mounted upon a convenient platform H', in this instance carried from the supporting-girders of the main apparatus.

These engines would be provided with reversing mechanism.

A horizontal shaft I is arranged at the side of the vertical shafts G G. This shaft is driven from the engines H through gears h and carries worms I' I', meshing, respectively, with the worm-wheels G' G'. The worms I' I' are mounted loosely upon the shaft I, but may be each rigidly secured thereto by a sliding 10 clutch K, here shown to be of an ordinary type, or, in other words, a jaw-clutch comprising a clutch member k, attached to each worm I', and a clutch member k', movable lengthwise of the shaft I, but compelled to 15 rotate therewith by an engaging feather and groove, the opposed faces of the clutch members being provided with engaging teeth or jaws. For operating these adjustable members k' and k' I provide the same with circumferential grooves k², into which a yoke k³ extends. It is of course necessary that the members k' k' be moved toward and away from each other simultaneously if the 20 clutches are located between the shafts G, 25 since the worms I' I' and the shaft I should be in operative connection or disengagement both at the same time. To this end I provide separate bars k⁴ k⁵, movable lengthwise in convenient bearings and to which the 30 yokes k³ are secured, the bars being themselves moved to and fro by a hand-lever k⁶, fulcrumed to a suitable stationary part. Connecting-rods k⁷ k⁸ connect the bars k⁴ k⁵ to the hand-lever k⁶ on opposite sides of its 35 fulcrum-point.

Extending laterally from each housing C is a short rotary shaft L, supported in suitable bearings and carrying a spur-wheel L', which is rigidly secured to the shaft and engages 40 with a pinion l, carried by the shaft I. Each pinion l is in operative connection with the shaft I, through the medium of a clutch L², whose construction may be similar to that already described.

45 From the shafts L power is derived for effecting the adjustment of the side rolls B B. To secure this result, I provide each shaft L with a bevel-pinion L³, coacting with a bevel spur-wheel L⁴, secured to the upper end 50 of an inclined shaft L⁵. These inclined shafts may actuate screws M, by which the blocks D D, and consequently the side rolls B B, are carried toward and away from each other, as pointed out in the patent already referred to.

55 Instead, however, of carrying the supporting-frame of the inclined shafts L⁵ upon the movable blocks D D they may be rigidly secured to a stationary support, a construction which

is illustrated. In this case the shanks of the screws M will engage with the hubs of the 60 driving bevel-gears by a spline-and-keyway connection to permit of the lengthwise movement of the screw-shank through the gear.

As it may be desirable to throw both clutches L² into and out of engagement independently, I may provide a system of operating-levers and sliding bars similar to that already described in reference to clutches K K, comprising sliding bars m m', hand-levers m², and connecting-rods m³ and m⁴. 70

As it may be necessary to shift the housings C C laterally to widen or lessen the distance between the same, the shafts I, L, and L will be provided with keyways of sufficient length to permit of this movement. It will be seen 75 by this construction that I provide means whereby either set of side and top and bottom rolls may be adjusted independently of the other and also by a manipulation of the proper clutches connections may be made so that 80 both sets of rolls may be operated together.

Having described my invention, what I consider as new, and desire to secure by Letters Patent, is—

1. In a rolling apparatus, the combination 85 with top and bottom rolls and side rolls, of a single power-shaft, worms and worm-wheels with which said worms engage to secure the adjustment of the top and bottom rolls, clutches for operatively connecting with and disconnecting said worms from said shaft, pinions driven by said power-shaft, and driving mechanism for securing the adjustment of the side rolls, clutches for operatively connecting said pinions with said shaft and disconnecting them therefrom, and means for 95 operating the clutches, substantially as specified.

2. In a rolling apparatus the combination 100 of the power-shaft I, the shafts G, G, driving the screws F, F, the worm-wheels G' G' splined to the shafts G, G, the worms I', I' driven from the shaft I and engaging with the worm-wheels G', G', the clutches K, K the pinions l l driving the shafts L, L, and 105 the clutches L² L² for operatively connecting the pinions l, l, with the shaft I and disconnecting them therefrom, substantially as specified.

In testimony whereof I have signed my 110 name to this specification in the presence of two subscribing witnesses.

DE WITT CLINTON PRESCOTT.
